US00D981673S

(12) **United States Design Patent** (10) Patent No.: **US D981,673 S**
Libman et al. (45) Date of Patent: **** Mar. 21, 2023**

(54) **TRASH RECEPTACLE**

(71) Applicant: **The Libman Company**, Arcola, IL (US)
(72) Inventors: **Andrew D. Libman**, Champaign, IL (US); **Aaron Libman**, Champaign, IL (US); **Jon Franklin**, St. Joseph, IL (US); **Carlos Aguiar**, Burgo (PT); **Fernando de Jesus Santos**, Maceira Lra (PT)

(73) Assignee: **The Libman Company**, Arcola, IL (US)

(**) Term: **15 Years**

(21) Appl. No.: **29/779,902**

(22) Filed: **Apr. 21, 2021**

(51) LOC (14) Cl. **23-99**

(52) U.S. Cl.

USPC **D34/1**

(58) **Field of Classification Search**

(57) **CLAIM**

The ornamental design for a trash receptacle, as shown and described.

DESCRIPTION

FIG. 1 is a top, front perspective view of the claimed design for a trash receptacle;

FIG. 2 is a front view thereof;

FIG. 3 is a back view thereof;

FIG. 4 is a left view thereof; and,

FIG. 5 is a right view thereof.

The broken lines in the drawings depict portions of the trash receptacle that form no part of the claimed design.

1 Claim, 5 Drawing Sheets
